ILLUMINABLE DISPLAY

Albert Conrad Speaect, 2138 Minnekahta Ave.,
Hot Springs, S. Dak.

Filed Oct. 8, 1964, Ser. No. 82,097

Term of patent 7 years

(Cl. D1—12)

FIG. 1 is a front perspective view of an illuminable display sign, embodying my new design;

FIG. 2 is a front elevational view of the same;

FIG. 3 is an elevational view taken from one side thereof, the opposite side being the same as the side shown;

FIG. 4 is a rear elevational view of the same;

FIG. 5 is a top elevational view of the same; and

FIG. 6 is a bottom elevational view of the same.

The dominant features of my design reside in the portions shown in full lines, it being understood that the electric cord is broken away for convenience of illustration.

I claim:

The ornamental design for an illuminable display, as shown and described.
